COMBINATION PORTABLE ELECTRIC COOK- STOVE AND SPACE HEATER

Glenn W. Tammen, Park Ridge, Ill., assignor to St. Joe
Machines, Inc., St. Joseph, Mich., a corporation of
Michigan

Application October 28, 1955, Serial No. 38,627

Term of patent 14 years

(Cl. D81—10)

Fig. 2.

Fig. 1.

Fig. 3.

Fig. 4.

Figure 1 is a side elevational view of a combination portable electric cookstove and space heater in closed position, embodying my new design;

Figure 2 is a perspective view of the same;

Figure 3 is an edge view of the same in a flat position;

Figure 4 is a side elevation of the article in opened position as used for a cookstove;

Figure 5 is a top view of the article in the position of Figure 4;

Figure 6 is an elevational view of the article in open position resting on one side as used for a space heater; and

Figure 7 is a side elevation of the article with the sections folded back to back as used for a cookstove.

I claim:

The ornamental design for a combination portable electric cookstove and space heater, as shown.
